FOLD AWAY DESIGN MASTER

Frank J. Wehringer, 217 E. Adele, Anaheim, Calif.
Filed Aug. 12, 1963, Ser. No. 301,363
3 Claims. (Cl. 248—454)

This invention is directed to a Fold-away Design Master drafting board.

Numerous drafting boards are available to designers today to suit their varied needs and requirements. The available boards fall into two general classifications. The first is the smaller, thin light board without any auxiliaries, adapted for making small drawings with the use of a T-square and triangles. The other class comprises those boards which are semi-permanently installed. These boards are large and are adapted for use with a permanently affixed straight edge or drafting machine. These boards are conveniently carried upon a piece of furniture which comprises sturdy legs and has framing for rigid support of the board directly from the floor, and for its adjustment to different angular positions.

It is clear that such large boards are complete pieces of drafting room furniture which cannot be readily moved or put out of the way, and that the earlier mentioned small boards described above are of such nature that they are not suitable for large drawings and more permanent use because of the lack of rigidity, their lack of suitability for drafting machine or straight edge, and because they are not equipped to lie in position but flat upon a desk or table.

Accordingly it is an object of this invention to provide a drafting board having collapsible supporting means so that the drafting board may be properly supported on a table or desk when in use.

It is another object of this invention to design supporting means for a drafting board of such character that the supporting means may be folded for convenient transportation and storage of the drafting board.

It is another object of this invention to provide a drafting board of such size and stability as to be suitable for use with drafting machines and permanently installed straight edges and for the drafting of drawings of substantial size, and at the same time to provide collapsible supporting means for the drafting board which when supporting the board provide rigid support, but arranged for easy collapsibility of the support for proper storage.

It is an object of this invention to provide an economic and trouble-free drafting board supporting structure which can be collapsed for easy transportation and storage of the drafting board.

Other objects and advantages of this invention will become apparent upon study of the specification, and the attached drawings in which:

FIG. 1 is a side-elevation of the Fold-away Design Master collapsible drafting board of this invention;

FIG. 2 is a rear elevational view of the drafting board showing the supporting structure thereof in position for support;

FIG. 3 is a view of the back of the drafting board, rotated 90°, showing the supporting structure in the supporting position in full lines and in the folded position in dashed lines;

FIG. 4 is an end elevation of the special hinge construction for use in this collapsible drafting board;

FIG. 5 is an elevational view of the hinge of FIG. 4 taken along the line 5—5 of FIG. 4;

FIG. 6 is another elevation of the hinge of FIG. 4 taken along the line 6—6 of FIG. 5; and

FIG. 7 is a detail of the pivot portion of the ends of FIG. 4.

In summary, this invention is directed to a drafting board having at least two support panels which are hinged

2

on special hinges. These special hinges have stops which limit the opening of the hinge to 90°, and a spring to urge the hinge open to the aforementioned stops. Each of the support panels is mounted on at least two hinges so the support panels may be so opened to substantially 90° with respect to the back of the board, at which point the stops are engaged. The support panel hinges contain springs which urge the support panels toward the closed position parallel with the back of the board. Mounted upon each of the support panels by hinges securing it thereto is a stop. Each of these stops is of such configuration as to lie behind the support panel when it is closed, and to hold the support panel out against the support panel hinge stops when the support panel is opened and the stop is in place. The special hinges supporting the stop structure upon the support panel are spring urged toward the open position and have a stop which limits opening to 90°. Accordingly, when folded, the stops and support panels occupy a minimum of space and when swung into operative position they rigidly support the drafting board.

Further in more detailed understanding this invention will be obtained by a study of the following portion of the specification wherein the Fold-away Design Master is described with a reference to the drawings. The Fold-away Design Master is generally indicated at 10 and primarily includes a drafting board top indicated by the numeral 12, and support for the top 12, generally indicated by the numeral 14.

The drafting board top 12 comprises a standard flat wooden drafting board 16 which equipped with a conventional across the board straight edge 18. The straight edge 18 is furnished with an upstanding projection 20 throughout a substantial portion of its length to serve as a holder for pencils and other drafting equipment at a convenient position close to the draftsman. Alternatively to the projection 20, a groove can be formed in the straight edge 18 for the reception of such drafting implements. The straight edge 18 is maintained in position by suitable cords or wires 22 which pass around pulleys 24 mounted on the corners of the board. The threading of the cord or wire 22 around the pulleys 24 is such that when clips 26, attached to the straight edge 18, are secured to the appropriate strands of the cord or wire, 22, the straight edge 18 moves up and down the board parallel to its prior position. A spring 28 in the cord or wire 22 maintains tension therein.

The back of the drafting board top 12 is indicated at 30 and it is to this back that the supporting structure of this invention is secured for holding the board in a proper drafting position. The supporting structure comprises a pair of support panels 32 of generally triangular configuration. The longest edge 34 of the support panel 32 is adjacent the back 30 of the drafting board 16. The two remaining edges 36 and 38 are preferably of different dimensions so that the triangle is not an isosceles triangle with its base toward the bottom 30 of the board. As shown, the edge 36 is longer than the edge of 38 and thus the edges 36 and 38 form different angles with respect to the drafting board 16. Accordingly, the drafting board 16 stands at different angles when it is resting on the edge 36 as compared to when it is resting on the short edge 38 of the support panels 32. Accordingly two different angles of the board with respect to the horizontal are available by this means.

In order to maintain convenience of storage of the Fold-away Design Master, the support panels 32 are arranged so that they may be folded adjacent the back 30 of the drafting board 16. Blocks 40 are secured to the back 30, and carry hinges 42 of special design. These hinges are of such construction and such configuration that they have an inbuilt stop which pre-

vents the panel 32 from swinging away from the back 30 to a greater extent than is shown in FIG. 2. In other words, the hinges 42 having internal stops which prevent opening more than 90°. From the position shown, the panels 32 can be swung toward each other and inwardly toward the back of the drafting board 30 until they lie in parallel position therewith. Springs in the hinges 42 urge the panels 32 in such a direction.

Stops 44 are also generally in the form of triangles and are of such configuration that when secured to the panels 32 by hinges 46 they rest against the back 30 of the drafting board 16 to maintain the panels 32 in the open position, against the action of the springs in the hinges 42. The hinges 46 are also of special construction of somewhat different configuration than the hinges 42. The hinges 46 also include a stop which limits the motion of the hinges 46 to terminate motion of the stops 44 in a position generally perpendicular to the panels 32. Springs in the hinges 46 urge the stops 42 toward this position. The thickness of the hinges 46 and the stops 44 is such that when the stops 44 are folded against the panel 32, and the panels 32 are folded against the back 30 of the board 16, the panels 32 lie substantially parallel to the back of the board, as hereinbefore recited.

The stops at precision spread hinges 46 are shown in more detail in FIGS. 4 through 7. In these figures the hinges can be seen to comprise an inner member 48 and an outer member 50. Each of these members have substantially flat panels 52 and 54, respectively, which have holes 55 for securing the flat panels to the parts which are to be hinged with respect to each other. Lugs 58 are bent upward at substantially right angles to the substantial flat area of the panel 52 at the ends of the panel 52 to form a pivot point for the hinge 46. Similarly lugs 60 are bent upward at substantially right angles to the panel 54, in order to provide a pivot point for this half of the hinge 46. Holes 62 are provided in the lugs 60 and holes 64 are provided in the lugs 58 so that a hinge pin 66 may pass therethrough to provide hinging action of the panels 52 and 54 with respect to each other. The hinge pin 66 may be riveted at 68 if immovability is desired.

The dimension between the outer sides of the lugs 58 is substantially equal to the dimension between the inner sides of the lugs 60 so that the lugs 58 fit within the embrace of the lugs 60. The lugs 58 are provided with a protuberant stop projection 70 of such dimensions and in such position as to abut against the back edge 72 of the panel 54 when the panel 52 and 54 are at substantially right angles with respect to each other. This arrangement of the stop permits the hinge to close in such a direction that the panels 52 and 54 are substantially parallel to each other and to open to a point where the stop 70 abuts the edge 72 when these panels are at substantially right angles to each other. Accordingly, a precision gap hinge is defined which controls the stops 44.

A spring 74 is mounted around the hinge pin 66 and tails of this spring 74 are arranged to be in engagement with the panels 52 and 54. Accordingly, the spring tail 76 is in engagement with the panel 52 and the spring tail 78 is in engagement with the panel 54. The spring 74 is wound in such a manner, and is mounted in the proper tension so that the hinge 46 is urged in the open direction

to a point where the stop 70 is in engagement with the edge 72; that is, the spring is urged to the open, right angle position. Thus it can be seen that when this hinge is mounted on the support panel 32 to carry thereon the stops 44, the stops 44 are urged in the direction at right angles to the support panels 32. In this position the stops hold the support panel 32 in supporting position, and when the stops 44 are folded against the action of the hinges 46 against the support panel 32, and the support panels 32 are folded against the back 30 of the board 16, the stops 44 are urged out of this position. To overcome this force, the hinges 42 contain springs which urge the support panels 32 toward the closed position where they are parallel to the back 30 of the board 16.

It is obvious to those skilled in the art that this invention is susceptible to various modifications and changes within the skill of the routine engineer. Accordingly the scope of this invention is as defined by the scope of the following claims.

I claim:

1. In a drafting board;
support means for said drafting board, said support means including first and second support panels adapted to support said drafting board at first and second angles;
means on said support panels to remove said support panels from supporting position with respect to said drafting board; and
means on said support panels for maintaining said support panels in drafting board supporting position, said means for maintaining said support panels including a stop hingedly secured to each of said support panels, said hinged support being hinged with built in stops to limit the opening of said hinges to substantially right angles with respect to said support panels, and a spring in said hinge to urge said hinge open against said hinge stop.

2. The structure of claim 1 wherein said means on said support panels to remove said support panels is hinged mounting for said support panels mounted upon the drafting board, said hinged mounting including springs urging said support panels out of support position with respect to said drafting board.

3. The structure of claim 2 wherein said hinges mounting such support panels contain stops which limit the opening of such support panels to substantially right angles with respect to said drafting board.
